CLAIM

The ornamental design for a hinge, as shown and described.

DESCRIPTION

FIG. 1 is a front perspective view of a hinge cover shown reduced in scale for ease of illustration and mounted onto a fence post and gate;

FIG. 2 is a front perspective view of the hinge of FIG. 1;
FIG. 3 is another front perspective view of the hinge of FIG. 1;

FIG. 4 is a front plan view of the hinge of FIG. 1;

FIG. 5 is a rear plan view of the hinge of FIG. 1;

FIG. 6 is a top plan view of the hinge of FIG. 1;

FIG. 7 is a bottom plan view of the hinge of FIG. 1;

FIG. 8 is a left end view of the hinge of FIG. 1; and,

FIG. 9 is a right end view of the hinge of FIG. 1.

The broken lines in the drawings are included for the purpose of illustrating unclaimed features and form no part of the claimed design.

1 Claim, 8 Drawing Sheets
